UNITED STATES PATENT OFFICE.

JOHN FREDRICK MAKOWSKI, OF BERKELEY, CALIFORNIA, ASSIGNOR TO TELEPHONE APPLIANCE COMPANY, A COPARTNERSHIP CONSISTING OF JOHN F. MAKOWSKI, EDWARD C. MORAN, EDWARD A. FORDE, AND GEORGE F. HILTON, ALL OF SAN FRANCISCO, CALIFORNIA.

TELEPHONE ATTACHMENT.

1,179,642.

Specification of Letters Patent. Patented Apr. 18, 1916.

Application filed August 14, 1913, Serial No. 784,702. Renewed November 17, 1915. Serial No. 62,074.

To all whom it may concern:

Be it known that I, JOHN FREDRICK MAKOWSKI, a citizen of the United States, residing at Berkeley, in the county of Alameda and State of California, have invented 5 a new and useful Telephone Attachment, of which the following is a specification in such full and clear terms as will enable those skilled in the art to construct and use the 10 same.

This invention relates to a device for holding the earpiece of the ordinary desk telephone, the object being to provide means whereby the switch lever may be held down 15 or allowed to rise to connect the service with central without having to hold the earpiece in one hand.

Another object of the invention is to so place the earpiece as to have it and the 20 mouthpiece in the proper position to receive and transmit the conversation without disconnecting them.

Other objects of the invention will be apparent as the description proceeds.

25 In the drawings, in which the same numerals of reference are applied to the same portions throughout the several views, Figure 1 is a front elevation of a desk telephone having this attachment applied thereto, Fig.

30 2 is a view of the attachment and telephone at right angles to Fig. 1, Fig. 3 is a plan view of the band which holds the attachment to the telephone standard, and Fig. 4 is a side elevation of one form of the earpiece 35 supporting lever in which a spring steel of brass wire is used in the place of a flat plate.

The numeral 1 indicates the base of the telephone, 2 the standard, 3 the receiver and 4 the mouthpiece at the upper end of the 40 standard. Projecting from the side of the standard is a forked lever 5 which commonly supports the receiver and which lever operates switch points to disconnect the local station from central in a manner which 45 forms no part of this invention, and which is therefore, not shown herein.

Secured to the standard at a suitable elevation is a band 10, a screw 11 clamping the

band in place. This band pivotally supports an upwardly extending lever 12, and it has a 50 stop 13 against which said lever lies when the receiver is in use. The lever 12 has a cam thereon which holds the lever 5 down when the receiver is not in use, as indicated in full lines in Fig. 1. The lever 12 is 55 twisted at 14 to present the earpiece to the user at the desired angle with respect to the mouthpiece, and another band 15, similar to the band around the standard is passed around the body of the earpiece and is secured, together with the earpiece, to the upper end of the lever 12, the screw by which 60 said band is secured in place enabling the earpiece to be still further adjusted in angle to suit the user. 65

In use the pivot point of the lower end of the lever 12 is so placed as to enable said lever to pass the vertical whenever the earpiece is in use, or out of use, thus enabling it to remain in either desired position. Of 70 course, in one position the telephone may be used and in the other its switches cut it out of the service.

The lever shown in Fig. 4 is made of wire 75 formed with loops at 15 and 16, the wire at the latter loop being long enough to form the cam 17.

It is to be observed that the receiver holder may be placed in the most convenient position for the operation of the switch arm 80 5, it being unnecessary to have the receiver exactly at right angles to the transmitter for the reason that it is only necessary to speak in front of the transmitter to effect 85 the sending of the speech.

Having thus described my invention what I claim as new and desire to secure by Letters Patent of the United States, modifications within the scope of the claim being expressly reserved, is as follows:

An attachment for telephones comprising 90 a clamp having a portion adapted to encircle a telephone standard and two adjacent parallel portions, one of which carries a stop over-lapping the end of the other portion, a 95 thumb screw to secure the clamp on the

standard, an arm pivotally connected with the clamp adjacent the stop thereon, said arm having a cam adapted to depress the receiver hook and hold it down, and a receiver clamp pivotally connected with the top of said arm.

In testimony whereof I have hereunto set

my hand this 4th day of August A. D. 1913, in the presence of the two subscribed witnesses.

JOHN FREDRICK MAKOWSKI.
